UNITED STATES PATENT OFFICE.

PIERRE POMEON, JOSEPH POMEON, AND ANTOINE LEON POMEON, OF ST. CHAMOND,
FRANCE.

MANUFACTURE OF PASTEBORD CASES AND MEANS THEREFOR.

1,388,888.

Specification of Letters Patent. Patented Aug. 30, 1921.

Application filed March 4, 1919. Serial No. 280,578.

To all whom it may concern:

Be it known that we, PIERRE POMEON, JOSEPH POMEON, and ANTOINE LEON POMEON, citizens of the French Republic, 5 of St. Chamond, Loire, France, have invented certain new and useful Improvements in the Manufacture of Pasteboard Cases and Means Therefor, of which the following is a specification.

10 This invention mainly consists in a method and means for the utilization of sheet pasteboard instead of thin sheet metal for obtaining stamped cases, boxes and the like, comprising an annular flange or 15 strengthening rib at the intersection of the bottom and the base of the cylinder. Further, the boxes may be of any suitable shape, and have one or more flanges or ribs.

The method consists in effecting the 20 stamping of the case in such a manner that there may be a surplus either in the length of the cylinder of the case, or in the surface of the bottom, then in forcing the said surplus, while compressing it, into an annular 25 neck of the mold, of which neck this surplus material takes the shape and size.

The annexed drawings illustrate the invention.

Figures 1 to 3 illustrate in section a mold 30 device in successive positions, Figs. 5 and 6 show a second device in successive positions: Fig. 4 is an elevation view of the case so manufactured. Figs. 7 to 16 illustrate further modifications which will be described 35 hereinafter.

The device shown in Figs. 1 to 3 enables the stamping of the case and the formation of the flange to be obtained in a single operation. It is composed:

40 1. Of a mold *b* having at its center a cylindrical passage *c*, both edges of which are splayed, and comprise each an annular groove; the upper groove has a determined diameter and height for receiving the paste- 45 board disk *r* to be stamped; the lower groove *d* is of dimensions corresponding to those of the flange to be obtained on the case.

2. Of a form-piece *a* in which is fitted the mold *b* and which is fastened on a stamping 50 press of any known type.

3. Of the stamping-tool which comprises a cylinder *e*, the tail-piece of which is fixed to the plunger of the press, and a piston *h* held in said cylinder by screws *f* screwed

into the wall of the said cylinder and the 55 points of which project inside the latter to lodge it in an annular groove *i* provided on the surface of the piston. Two Belleville washers *g* are disposed in contrary directions between the bottom of the cylinder *e* 60 and the upper surface of the piston *h*. These washers form a spring and constantly push the piston outward against the screws *f* which form abutments, and the 65 position of which on the cylinder determines the extent of projection of the lower surface of the said piston below the cylinder *e*.

The said cylinder *e* has two external diameters. The greater diameter is the same 70 as the inner diameter of the opening *c* of the mold, with a slight play, however, to allow the sliding of the said cylinder in this mold. The smaller diameter *m* is so measured that the annular space existing between its 75 surface and that of the opening *c* may be equivalent to the thickness of the pasteboard disk *r* to be stamped.

The height of the projection made by the lower surface of the piston *h* below the edge 80 of the cylinder *e* is also measured to correspond with the excess height which the cylinder of the case *r* is to have during its stamping in order to allow the obtaining of the flange. The diameter of the pasteboard 85 disk *r* is also determined from the amount of said excess.

The operation is as follows:—The members being in the position of rest, Fig. 1, a pasteboard disk *r* is placed by hand above 90 the mold in the groove destined to receive it: the press is then actuated to lower the plunger and its tool *e*, *h*, which enters into the opening *c* of the mold driving the paste- 95 board *r* which is stamped as represented by Fig. 2 where the case is shown partially formed without the flange. At that moment the height of the cylinder of the case equals the sum of the heights of the part *m* and of the projection of the piston *h*.

The cylinder *e* and the piston continuing their descending movement, the piston stops when the bottom of the case *r* encounters the form-piece *a*, but the cylinder *e* still pursues its course and the edge of its greater 105 diameter presses on the edge of the pasteboard in order to force back on itself the cylindrical part of the latter. The result

is that this longitudinal compression of the pasteboard compels the lower part of the cylinder of the case *r* to extend laterally and fit into the groove *d* of the mold, assuming 5 the shape of this groove, as is well shown by Fig. 3.

The pasteboard case obtained by this 10 stamping has now only the height of the part *m* of the cylinder *e* and the flange *s* has the same thickness as the pasteboard, but it could be of less or greater thickness; it 15 would suffice to give the groove *d* a determined height. The projection of the said flange can also be varied by giving the groove *d* a suitable breadth. Fig. 4 shows in external view the case *r* with its flange *s* as formed by the stamping operation which has just been described.

When the cylinder *e* has effected its whole 20 course, it has compressed the spring-rundles *g* and at the re-ascent of this cylinder, these springs push back the piston *h* and cause it to resume its normal position Fig. 1. The mold *b* is also arranged so that it can be 25 raised above the form-piece *a* after the ascent of the cylinder *e*. This elevation of the mold is necessary in order to be able to disengage and remove the manufactured case.

After the removal of the case, the mold 30 descends again to resume its place in the form-piece *a*, the operator puts in place a fresh pasteboard disk and actuates the press. The same operations which have been described are recommenced.

35 The second method necessitates two successive operations. The first consists in stamping a pasteboard disk in order to obtain a single case, the bottom of which, however, has a certain convexity, as shown by Fig. 5. Such a case *r* is then placed upside down in a mold *o*. A cylindrical mandrel *p* is previously inserted in this case, the diameter of which is that of the case and the height equivalent to that of the cavity provided 40 in the mold *o* from the bottom to the groove *d*.

The excess pasteboard is now in the bottom *t* of the case which forms a dome over the mandrel *n* and the mold. To the plunger 50 of the press is fixed a circular plate *n* which descends on the mold and flattens the dome *t* of the case against the upper surface of the mandrel. The pressure exerted by this plate on the bottom of the said case 55 spreads said bottom on the surface of the mandrel and forces the circumferential part to expand into the annular groove *d* of the mold and to form a flange *s*, Fig. 6, similar to that obtained by the first device.

60 In this latter device the mold is fixed, as the manufactured case can easily be removed when the plate *n* is raised again.

In the drawing a case of small height has 65 been represented, but the method and the devices for executing it allow cases to be ob-

tained of several centimeters in height and of any desired diameter, as well as flanges of variable projection and any section, according to the uses for which the cases are intended.

In the device, Figs. 7, 8, and 9, employed 70 for obtaining two flanges on one box, the mold *b* still comprises the upper groove *l* and the lower one *d*, but it also comprises a third groove *d*₁, parallel with the two others 75 and situated between them, near the groove *d*, at a distance which varies with the height of the box to be manufactured.

The stamping tool is similar to that hereinbefore described, and the stamping operation is the same, the cardboard disk *r* is still placed above the mold in the groove *l*, then the tool is moved down. The length of the piston *h* is such that the cylinder *e* does not 80 reach the bottom of its course when the base of the piston *h* flattens the disk *r* against the plate *a*, as shown in Fig. 8. In this position of the tool, the cylindrical part of the case *r* has already been compressed by the cylinder *e* and the angle of the case begins to be 85 forced into the groove *d*.

The tool continuing its descendent course, the compression of the cylindrical part of the case also continues until the base of the cylinder *e* reaches the disk *r*, the final position of the stroke being shown in Fig. 9. During this final compression, the cardboard is completely forced into the groove 90 *d* and simultaneously into the intermediate groove *d*₁.

The case thus stamped consequently possesses two flanges, one *s*, at the intersection of the bottom and sides of the box, the other *s*₁ extending outside these sides between the flange *s* and the edge of the box.

Fig. 10 represents a box of rectangular shape and a lid *r*₁ of like shape, which has only one flange *s*₂. The intermediate flange *s*₁ serves as abutment to the lid.

It is understood that the boxes or cases obtained by the process can be of all desired 100 shapes. It suffices to give required shapes to the hollow interior *c* of the mold and to cut out the sheet of cardboard to be stamped in the selected sizes and shapes.

Two or three intermediate flanges would be obtained, if necessary, by the same means as that above described for the flange *s*₁.

It is necessary that the mold should be 105 constructed in two or more jointed parts and capable of opening, in order to allow the removal of the case or of the box having one or more intermediate flanges. By way of example, Figs. 13 to 16 show a mold in two parts A A jointed at O and each having a pin G engaged in an oblique slide B provided in a vertical plate C moving from the bottom upward or vice versa for the opening or closing of the mold. The latter is placed on a block not illustrated 110 115 120 125 130 135 140 145 150 155 160 165 170 175 180 185 190 195 200 205 210 215 220 225 230 235 240 245 250 255 260 265 270 275 280 285 290 295 filling the same function as the plate *a* hereinbefore described; the plate *C* slides in appropriate guides and is driven by any mechanism (cam, lever, etc.), actuated by means 5 of a pedal, for instance, within reach of the operator.

It is understood that the descending movement of the plate *c* causes the meeting of the pins *G* and the closing of the mold *A*, the position in Figs. 13 and 14 corresponding to the stamping stage. The ascending movement of said plate, on the contrary, determines the separation of the pins and the opening of the two parts *A*, a position in Figs. 15 and 16 corresponding to the stage of removal of the box or of the stamped case.

The stamping apparatus for the cases with one or more flanges can be arranged 20 for the automatic ejection of the manufactured case, as shown by the example in Figs. 11 and 12.

The mold *b* arranged for a single flange is mounted on the table *D*, so as to leave between it and the upper surface of said table a recess serving as a slide to a movable drawer *T* in which is provided an opening *E* of which the shape and size correspond to those of the case or stamped box *R*. The 30 table *D* has an opening *H* similar to opening *E* and which is underneath and in the axis of that of the mold. The drawer is worked, for instance, by means of a finger *F*, Fig. 12, which receives a reciprocating 35 movement from any mechanical device driven by a pedal actuated by the operator.

For the stamping operation, the drawer *T* must be in the position of Fig. 11, where its solid hinder part is arranged below the 40 cavity of the mold and forms the bottom thereof. When the stamping is finished the operator actuates the pedal to make the drawer return into its slide to the position of Fig. 12, where its opening *E* coincides with 45 that of the mold and that, *H*, of the table. At that moment the operator actuates the hand-wheel in the desired direction in order to cause a fresh descent of the stamping tool, which has the effect of pushing from the top 50 downward the manufactured case and obliging it to detach itself from the tool when it arrives outside the mold. Fig. 12 shows the tool and the case halfway in the process of ejection. In order to facilitate the removal of the case, two or three claws can 55 be placed around the wall of the opening *E*, said claws formed of a spring arranged so as to prevent the case from reascending with the tool and insure its rejection. The case 60 will fall into a basket or any receptacle placed underneath the machine.

In the case of boxes with several flanges, the drawer will return into position after the 65 raising of the plate *C*, and consequently when the two parts of the mold are separated

from each other. The box will detach itself in most cases, but its removal can be insured by lowering the tool to a slight extent.

The devices just described can be advisably combined with a hand press or mechanically driven stamping presses in order to produce a rapid manufacture of any stamped boxes or cases in strictly exact dimensions.

What we claim as our invention and desire to secure by Letters Patent of the United States is:—

1. In an apparatus for the purpose described, the combination of a mold having an annular groove in its inner face, a mandrel or plunger comprising a tubular member, adapted to enter the mouth of the mold, a piston like member adjustably connected with the tubular member and arranged to extend through the end thereof that co-operates with the mold, and means acting to maintain the piston in projected relation to the tubular member and to permit the piston to be forced into said tubular member during the pressing operation, for the purpose specified.

2. In an apparatus for the purpose described, the combination of a mold having an annular groove in its inner face, a mandrel or plunger comprising a tubular member, adapted to enter the mouth of the mold, the end portion of the section of said member that enters the mold being of less area than the body of said section, a piston like member adjustably connected with the tubular member and arranged to move through the end of the tubular member within the mold, and yielding means within the tubular member acting to project the piston beyond the end of the tubular member, for the purpose specified.

3. In an apparatus for the purpose described, the combination of a mold having an annular groove in its inner face, a mandrel or plunger comprising a tubular member, adapted to enter the mouth of the mold, and provided with an annular exterior shoulder on that portion that enters the mold, a piston adapted to move through the end of the tubular member within the mold, spring means acting to cause the piston to project from the tubular member, and means for limiting movement of the piston by said spring means.

4. An apparatus for the purpose described, comprising a mandrel composed of a hollow cylinder, a solid piston within and having one end adapted to project beyond the edge of the hollow portion of the cylinder, springs mounted inside the cylinder and bearing on the piston, fixed abutments limiting the projection of said piston, the diameter of the base of the cylinder being externally decreased in order to form an annular groove of height equal to that of the

walls of the finished article, and of a depth corresponding to the thickness of the sheet of cardboard, the said mold having a groove at the base of its inner wall for receiving 5 the excess cardboard which is forced in by means of the shoulder of the annular groove at the descent of the mandrel.

5. In an apparatus for the purpose described, the combination of a mold having 10 an annular groove at the base end of its inner surface and a second similar groove above said base end, a plunger comprising a tubular member having an exterior shoulder about the portion that is adapted to enter 15 the mold and a piston movable through the end of the tubular member within the mold, and yielding means interposed between the piston and the tubular member and acting to normally cause the piston to project beyond the end of the tubular member, for 20 the purpose described.

6. In an apparatus for the purpose described, the combination of a mold having an annular groove at the base end of its inner surface and a seat for a blank at its 25 open end, a plunger movable into the mold and provided with an exterior annular shoulder and with a telescoping piston, of less area than the plunger body below said shoulder, and spring means within the plunger acting to normally project the piston therefrom. 30

In witness whereof we have signed this specification in the presence of two witnesses.
